UNITED STATES PATENT OFFICE.

WILLIAM F. GEHRIG, OF NEWARK, NEW JERSEY, ASSIGNOR TO ESSEX SPECIALTY CO., INC., OF BERKLEY HEIGHTS, NEW JERSEY, A CORPORATION OF NEW JERSEY.

DETECTOR FOR WIRELESS-TELEPHONE OUTFITS.

Application filed March 9, 1922. Serial No. 542,357.

To all whom it may concern:

Be it known that I, WILLIAM F. GEHRIG, a citizen of the United States, residing at Newark, in the county of Essex and State 5 of New Jersey, have invented certain new and useful Improvements in Detectors for Wireless-Telephone Outfits; and I do hereby declare the following to be a full, clear, and exact description of the invention, such 10 as will enable others skilled in the art to which it appertains to make and use the same, reference being had to the accompanying drawings, and to characters of reference marked thereon, which form a part 15 of this specification.

This invention relates, generally, to improvements in detectors for use in connection with wireless telephone apparatus; and the invention has reference, more particularly, to a novel construction of the so 20 called "cat-whisker" or galena detector for wireless telephone receiving sets.

The invention has for its principal object to provide in a cat-whisker detector an 25 improved construction of galena cup holder together with a novel adjustable self-locking cat-whisker support or carrier, which may be quickly and easily manipulated to search out with the cat-whisker terminal 30 the most sensitive or effective spot of the galena detector body, and which, when said spot is found, operates to automatically fix or lock the support or carrier to hold said cat-whisker terminal in registration and 35 contact therewith, thus avoiding all necessity for employing additional or separate locking means, the manipulation of which would tend to disturb and frequently to dislodge the cat-whisker terminal from the 40 contact position relative to the detector body which has been found most desirable and effective.

Other objects of this invention, not at 45 this time more particularly enumerated, will be clearly understood from the following detailed description of the same.

With the various objects of this invention in view, the same consists, primarily, in the novel construction of cat-whisker detector hereinafter set forth; and, furthermore, the invention consists in the novel arrangements and combinations of the various devices and parts, as well as in the 50 details of the construction thereof, all of

which will be hereinafter more fully described and claimed. 55

The invention is clearly illustrated in the accompanying drawings, in which:—

Figure 1 is a plan view of the novel construction of cat-whisker detector, made 60 according to and embodying the principles of this invention; Figure 2 is a part side elevation and part vertical longitudinal central section of the same; Figure 3 is a bottom view; Figure 4 is a transverse section of the same, taken on line 4—4 in 65 said Figure 1, the base being shown in elevation; Figure 5 is a detail edge elevation of a bearing clip employed in connection with the cat-whisker terminal support or carrier; and Figure 6 shows a modified form of carrier rod support. 70

Similar characters of reference are employed in all of the hereinabove described views, to indicate corresponding parts. 75

Referring now to said drawings, the reference character 6 indicates a base, made of a suitable insulating material, upon which the operative parts of the detector are mounted. 80

The reference character 7 indicates a metallic cup or block in which is imbedded and fixed a detector body 8, frequently consisting of sulphuret of lead, commonly called galena. Said cup or block 7 is secured in mechanical attachment to the base 6, and in electrical circuit with other elements of a wireless telephone receiving set, by means of a horizontal metallic cup-holder or clip body 9, which is provided at 85 one end with up-turned or vertical flanges 10 springing from the sides of said cup-holder or clip body 9, so as to be laterally opposed to each other, said flanges 10 terminating at their outer ends in a pair of 90 laterally opposed spring-like gripping or clip arms 11, into the embrace of which said cup or block 7 is sprung, so as to be frictionally gripped and supported thereby. The opposite end of said cup-holder or clip 100 body 9 terminates in a perforate ear or tail-piece 12, which lies in the plane of said cup-holder or clip body 9. Said cup holder or clip body 9 is supported upon the upper surface of said base 6, preferably in an 105 oblique position so that the cup or block 7 with its detector body 8 is substantially in central disposition intermediate the sides

of said base, and so that the perforate ear or tail piece 12 is disposed at one end of said base adjacent to one side or corner thereof. Engaged and alined with the perforate ear or tail piece 12, thus disposed, is a binding post 13, which is secured to said base 6 by a fastening screw 14, which extends upwardly through and from the bottom of said base, 5 and thence through said perforate ear or tail-piece 12 to screw into the lower end of said binding post 13, thereby both securing said cup holder or clip body in electrical engagement with said binding post 10 13, as well as mechanically securing said parts in the desired fixed positions upon said base 6.

Arranged upon said base 6, for cooperation with said detector body, is a novel adjustable self-locking cat-whisker terminal support or carrier, the same comprising a metallic bearing clip or bracket provided with a bottom portion 15 which rests upon said base 6, preferably in a central position 15 intermediate the sides of the latter, and longitudinally alined with and spaced from said detector body supporting means. Integrally connected with the respective sides of said bottom portion 15 are upwardly extending standard members 16, which are laterally spaced apart and opposed to one another. Said bearing clip or bracket is preferably made of sheet metal, of such qualities that said standard members 16 are 20 possessed of a requisite degree of springiness or resiliency. Normally said standard members 16 are inclined toward or converge somewhat toward each other, as shown in Figure 5, so that when moved apart, they 25 will be placed under a tension tending to move the same toward each other, and thereby will grip any element supported between the same under such conditions. Said standard members 16 are provided, adjacent to 30 their upper free ends with circular bearing openings or seats 17 which are transversely alined one with the other. Interposed between said standard members, so as to be engaged thereby and seated movably relative to said bearing openings 17, is a split spherical carrier consisting of two, preferably separate, substantially hemispherical members 18 and 19 having their rounded outer faces respectively seated or journaled 35 in the respective bearing openings or seats 17 of said standard members. Said hemispherical members may be joined together by a narrow integral neck x , if desired, as shown in Fig. 6. Said hemispherical members 18 and 19 are preferably hollow (although it is not absolutely essential that they should be), and their opposed sides or margins are each provided with indentations or notches 20 diametrically alined so as to 40 form seats or guideways for engaging an

adjustable metallic carrier rod 21 which is interposed between said hemispherical members 18 and 19 so as to be supported thereby in diametrical extension therebetween in such a manner as to be capable of a longitudinal movement and also an axial rotary movement relative thereto. Said carrier rod 21 is provided at its inner end with a resilient cat-whisker contact terminal 22 of suitable form, and secured upon the outer 70 end of said carrier rod 21 is a handle portion 23, made of a suitable insulation material, and serving as a means for grasping the carrier rod when manipulating the same to adjust the contact terminal 22 relative to 75 the detector body 8. The bottom portion 15 of said bearing clip or bracket is secured by a fastening screw 24 to said base 6, and is additionally secured, and at the same electrically connected with a conductor 25 imbedded in the bottom of said base 6, by means of the bolt 26 and nut 27, as shown in Figures 2 and 3. The said conductor 25 extends to the fastening screw 28 which secures a binding post 29 to the base 6. The 80 detector is electrically connected in circuit with the other elements of a wireless telephone receiving set, by connecting the proper circuit wires to the respective binding posts 13 and 29, so that the circuit is established when the cat-whisker contact terminal is brought into engagement with the 85 detector body.

It will be noted from an inspection of the drawings that said carrier rod 21, by reason 90 of the operation of the novel means for supporting the same, is capable of a universal adjustment, whereby the cat-whisker contact terminal carried thereby may be readily moved to search out and engage any spot 95 on the exposed surface of the detector body 8. The adjustable movements rendered possible to the carrier rod by said novel supporting means are four-fold, viz., oscillatory movement in a horizontal plane (as 100 indicated in Figure 1); oscillatory movement in a vertical plane (as indicated in Figure 2); longitudinal reciprocable movement (as also indicated in Figure 2); and rotary movements about its longitudinal 105 axis. Owing to the fact that said resilient or spring-like standards 16 are placed under a tension when the parts are assembled, it follows that the hemispherical members 18 and 19 will be pressed toward each other, 110 thereby frictionally engaging and gripping the carrier-rod supported intermediate the same, so that oscillatory movements, in either horizontal or vertical planes, which are imparted to said carrier rod will be 115 transmitted to said hemispherical members 18 and 19, which will consequently pivot or fulcrum such movements by reason of the rotation of the members 18 and 19 in the bearing openings 17 of the standards 16, 120 125 130

without danger of disengaging the carrier-rod from its operative assembled relation between said hemispherical members. To move the carrier rod longitudinally, or to 5 rotate the same on its longitudinal axis, sufficient force, properly directed, is applied to the same to overcome the frictional grip of said hemispherical members, so that the carrier-rod will slide on the seats 20.

10 While the supporting means for mounting the carrier rod will thus readily admit of a desired range of four-fold movement as described, said means, by reason of its character and construction, provides a very im- 15 portant additional function, viz., that the carrier-rod 21 will be frictionally gripped and held stationary in any position to which it has been adjusted, and consequently when once disposed to place the cat-whisker contact terminal in desired contact relation with the detector body 8 it will be automatically locked or held in such position, without necessity for employing separately manipulated locking means, such as set screws or the 20 like, the operation of which might tend to disturb the delicate adjustment of the cat-whisker terminal. This advantageous functioning is due to the fact that the spring-like standard members 16 bear frictionally 25 against the hemispherical members 18 and 19, and in turn force the latter into frictional binding engagement with the carrier-rod, and consequently such frictional resistances thus established, tend first to bind or hold 30 the hemispherical members 18 and 19 against free rotation relative to the bearing openings 35 of the standards 16, and, second, tend to bind or hold the carrier rod against free longitudinal or rotative movement relative 40 to the hemispherical members; such movements being possible only when a proper manipulative force sufficient to overcome such resistances are applied.

I am aware that some changes may be 45 made in the various arrangements and combinations of the devices and parts, as well as in the details of the construction of the same without departing from the scope of this invention as set forth in the foregoing 50 specification, and as defined in the appended claims. Hence, I do not limit my invention to the exact arrangements and combinations of the various devices and parts as described in said specification, nor do I confine myself 55 to the exact details of the construction of said parts as illustrated in the accompanying drawings.

I claim:—

1. In a device of the kind described, a 60 fixed detector body, a pair of electrically conductive opposed resilient standards having bearing openings, a split spherical body of electrically conductive material disposed intermediate said standards with its opposite 65 convex surfaces rotatably journaled in said 130

bearing openings, a metallic carrier rod extending diametrically through said split spherical body so as to be frictionally engaged thereby but movable relative thereto, and a cat-whisker contact terminal carried 70 on one end of said carrier rod for cooperation with said detector body.

2. In a device of the kind described, a fixed detector body, a pair of opposed standards having bearing openings, a pair of 75 hemispherical members intermediate said standards having their convex faces seated respectively in said bearing openings, said standards being under a spring tension tending to press said hemispherical members together, said hemispherical members having aligned diametrically disposed seats at their opposed faces, a carrier rod extending between said hemispherical members and frictionally engaged by the seats thereof, and 80 a cat-whisker terminal carried on one end of said carrier rod for cooperation with said detector body.

3. In a device of the kind described, a 85 cat-whisker contact terminal mounting, comprising a pair of opposed resilient standards having bearing openings, a split spherical body intermediate said standards with its opposite convex surfaces rotatably journaled in said bearing openings, a carrier rod 90 extending diametrically through said split spherical body so as to be frictionally engaged thereby, and a cat-whisker contact terminal fixed to one end of said carrier rod.

4. In a device of the kind described, a 100 cat-whisker contact terminal mounting, comprising a pair of opposed standards having bearing openings, a pair of hemispherical members intermediate said standards having their convex faces seated respectively in said 105 bearing openings, said standards being under a spring tension tending to press hemispherical members together, said hemispherical members having aligned diametrically opposed seats at their opposed faces, a carrier 110 rod extending between said hemispherical members and frictionally engaged by the seats thereof, and a cat-whisker contact terminal on said carrier rod.

5. In a device of the kind described, a base 115 of insulating material, a cup, a detector body mounted in said cup, a cup holder fixed on said base having opposed gripping flanges to embrace and hold said cup, a binding post connected with said cup-holder, a pair of 120 opposed standards having bearing openings fixed on said base, a second binding post on said base, an electric conductor interconnecting said second binding post with said standards, a pair of hemispherical members intermediate said standards having their convex faces seated respectively in said bearing openings, said standards being under a spring tension tending to press said hemispherical members to- 125 130

gether, said hemispherical members having alined diametrically opposed seats at their opposed faces, a carrier rod extending between said hemispherical members and frictionally engaged by the seats thereof, and a cat-whisker contact terminal mounted on one end of said carrier rod for cooperation with said detector body.

In testimony, that I claim the invention set forth above I have hereunto set my hand 10 this 25th day of February, 1922.

WILLIAM F. GEHRIG.
